UNITED STATES PATENT OFFICE.

GEORGE MASTERS, OF VICTORIA, TEXAS.

ATTACHMENT FOR LEAD-PENCILS.

SPECIFICATION forming part of Letters Patent No. 665,028, dated January 1, 1901.

Application filed February 27, 1900. Serial No. 6,736. (No model.)

To all whom it may concern:

Be it known that I, GEORGE MASTERS, a citizen of the United States, residing at Victoria, in the county of Victoria and State of Texas, 5 have invented a new and useful Attachment for Lead-Pencils, of which the following is a specification.

My invention relates to attachments for lead-pencils; and it has for its object to provide a lead-pencil with a calendar which is permanently secured thereto in such position that it may be unrolled for examination at any time and then return to its original position.

With this object in view my invention consists in the improved construction of a lead-pencil and the combination therewith of a calendar and means for confining the free ends of the calendar to the pencil, as will be hereinafter more fully set forth.

In the accompanying drawings, in which the same reference-numerals indicate corresponding parts in each of the views in which they occur, Figure 1 is an elevation of a pencil constructed in accordance with my invention with the calendar unrolled in position for observation. Fig. 2 is a longitudinal sectional view of the pencil with the calendar rolled thereon and having its free end secured in position.

In practicing my invention I provide a suitable body or roller 1, which may be an ordinary lead-pencil, with a suitable annular groove or recess 2 near its upper end and 5 with two outwardly-projecting studs or prongs 3 upon opposite sides of said recess.

4 indicates a calendar which is preferably adapted for a year, although it could be adapted for a shorter or longer length of time, if desired. The inner end of the calendar is pasted or otherwise suitably secured to the bottom of the recessed portion of the pencil and is wound thereon within the recess and has its outer end provided with a bar 5, each 5 end of which is provided with a perforation 6 in position to fit upon one of the studs or pins in the pencil and be retained thereon when the calendar has been rolled up.

I prefer to form the calendar of a strip of paper or of other thin flexible material of sufficient width to receive the numbers indicating the days of the month and of such length as to receive the number of months to be designated, the first month, as January,

being at the outer end and the last month, 55 as December, being at the inner end. The bar or cross-piece 5 is preferably formed from brass, or it may be formed from other material and have each hole provided with an eyelet for engagement with the pins 3. To prevent the accidental removal of the bar from the pins, I prefer to bend the outer end of the pins, as shown at 7, so that they must be bent slightly to permit the passage of the bar. I also reserve to myself the right to make 60 such other changes and alterations as will come within the scope of my invention.

As above described, it will be seen that my invention can be embodied in a lead-pencil very cheaply, as it is only necessary to form 70 the recess near the top of sufficient width and depth to receive the calendar when rolled therein. When it is desired to know the date, the bar is readily slipped off the pins 3 and the calendar unrolled until the desired date 75 is located. The calendar is then again rolled within the recess and the bars slipped over the yielding ends of the pins and the pencil can be used in the usual manner. By printing or otherwise forming the dates upon the 80 inner surface of the calendar they are always preserved from being soiled or worn by the usage to which the pencil may be subjected.

If desired, my improved calendar can be formed separately and applied to different 85 pencils by forming a metallic cylinder with an annular groove for the reception of the calendar and fitting an eraser in one end of the cylinder and fitting the other end over the top of the pencil. 90

Having thus fully described my invention, what I claim as new, and desire to secure by Letters Patent of the United States, is—

The combination with a body, a portion of which is provided with an annular groove, of 95 an outwardly-extending curved pin at each end of the groove, and a flexible sheet provided with a calendar permanently secured at one end to the body within the groove, the other end of which is provided with a bar, 100 each end of the bar extending beyond the edge of the calendar and being perforated for engaging with one of the pins, substantially as described.

GEORGE MASTERS.
